COLOR SETTING OF JUSTIFYING TYPEWRITERS

Pierre Léglise, Paris, France

Application August 2, 1952, Serial No. 302,309

3 Claims. (Cl. 197—84)

The present invention is directed to the setting of justifiers through the agency of colors in end-of-line justifying typewriters. In the so-called "end-of-line" justifying process as described in the application for patent Serial No. 215,748 filed March 15, 1951, under the title "Process and Apparatus for Justifying Typewritten Material," now Patent No. 2,696,286, the justification is effected by regular contraction or dilation of the typing in only the end portions of the lines, known as "terminal segments." The justifying mechanisms give the terminal segments of the different lines a common length, that of the normal terminal segment, a feature of construction in the typewriter.

The end-of-line justifying typewriters as the above application describes comprise but one normal terminal segment. On the other hand, those described in the application for patent Serial No. 297,939 filed July 9, 1952, under the title "End-of-line Justifying Typewriter," now Patent No. 2,705,554, comprise several of these segments. The possibility of choosing, for the justification of a given text, a normal terminal segment with a length as near as possible to the width of the required column, allows the carrying out of the dilations and contractions of the typing necessary to the justification on final parts of the lines systematically or occasionally longer than is permitted by typewriters with a single normal terminal segment; there results smaller rates of dilation and contraction. For example, in a typewriter with four normal terminal segments comprising respectively 30, 40, 50 and 60 characters, the texts intended to fit columns of 30 to 39 (40—1) characters are justified over the normal terminal segment of 30 characters, but texts intended to form columns of 40 to 49 (50—1) characters can be justified over the normal terminal segment of 40 characters, etc., and texts intended to fit columns of 60 characters or more can be justified over the normal terminal segment of 60 characters; whilst if the typewriter were reduced to the employment of only the first of these various normal terminal segments, simply the last 30 characters (on the average) of each line, would be, in every case, the object of contractions or dilations.

Whatever the number of normal terminal segments available, a given task is effected, usually, by employing only one of these segments: the longest possible of them for justifications after a preparatory typing, and, as a rule, the shortest for justifications at the first attempt. The present invention, which finds its main application in this last kind of justification, is however independent of the length of the normal terminal segment used.

In justifications at the first attempt, it is necessary to count the number of characters of the terminal segments, the term "character" applying equally here to the spaces between words. To this effect, the first of the above quoted applications anticipates the effecting of the blank typing of these segments on the space bar. On the other hand, according to the application for patent Serial No. 300,072 filed July 21, 1952, under the title "Blank Typing of Terminal Segments," the blank typings are effected on the whole of the keyboard, the impressions on the paper

2

being simultaneously prevented by a no impression device, without the rack and the carriage losing their mobility. Whatever the method of executing blank typings, the process of counting must be borne in mind for the understanding of the invention.

All ordinary typewriters are provided with a graduated rule, integral sometimes with the carriage, sometimes with the frame, and usually with an indicator showing the graduations of this rule; the indicator is mounted on the frame in the first case and on the carriage in the second.

When the graduated rule is integral with the carriage, it is, in most cases, the horizontal bar holding the paper against the platen by the intermediary of small rubber rolls (paper bail), which constitutes the said rule; the graduations can be read, for example, in line with the type guide serving as indicator. It however happens that the rule in question may be duplicated by a second rule, similarly graduated, which then moves usually behind a window or opening of the guide, and the graduations of which are read by means of some mark made at the base of the window. In any case, the indicator occupies a central position on the typewriter.

When the graduated rule is integral with the frame, the indicator is mounted in the plane of symmetry of the carriage.

To proceed on a fixed basis, it will be assumed in the following exposition of the counting process that the graduated rule is integral with the carriage and that the indicator is in the same vertical plane as the type guide.

When transforming such ordinary typewriters into end-of-line justifying typewriters in accordance with the process described in the above-quoted applications, care is taken, naturally, to give the indicator, as much as possible, such a position that the reading of the graduations may be easy.

To effect justifications with an end-of-line justifying typewriter, the member actuating the justifier is set on the frame with a view to causing the necessary contractions or dilations of the typing from a predetermined section of the platen, means being designed to announce the arrival in line with the type guide of the section in question; these means can be either the blocking of the carriage by the right hand margin stop or, better, the sounding of a bell. At the instant of this arrival, the indicator

points towards the graduation of the rule which constitutes, by definition, the beginning of all the terminal segments for the work in course of execution. Let this graduation be 55 for example. If the normal terminal segment utilized comprises, for example, 30 characters and the justification play covers from —4 to +4 characters, the terminal segments of the various lines will not be capable of comprising less than 26 (30—4) or more than 34 (30+4) characters. For ascertaining the number of characters which it will be possible to include

in the terminal segment of the line already partly typed, the typist continues the typing of the text either on the space bar after actuating the margin release or on the keyboard after engaging the no impression device. During this operation, the carriage shifts character by character, without the characters being printed and the successive graduations 56, 57, 58, etc. of the rule move past the indicator. When the graduation 85 (55+30) approaches this latter, the typist turns her attention to the eventual division of the word being blank typed. A hyphen being added if necessary, she observes, for example, that the graduation shown by the indicator is 84.

Thus the terminal segment lacks $85-84=1$ character and the justifier will have to be set to —1. (To take another example: if the indicator shows the graduation 87 of the rule, the terminal segment comprises $87-85=2$ surplus characters and the justifier will have to be set to +2.) The typewriter serves indeed as a counter of the charac-

ters during the blank typing, and the typist deduces a certain result from the counting thus effected. Then, bringing the beginning of the still blank portion of the line back to the type guide (i. e. the graduation 55 of the rule in line with the indicator), the typist sets the justifier to the required notch, disengages the no impression device if it has been employed; as the case may be, and effectively prints the terminal segment which, in emerging justified, justifies the line.

The reading of numerical graduations and the subsequent calculation, although elementary in character, are the cause of certain errors: the graduation marking the end of the normal terminal segment (85 in the particular case) can slip the memory—it varies indeed according to the work; a graduation can, from a distance, be mistaken for another; a negative setting can be confused with a positive. In brief, the satisfactory execution of justifications at the first attempt entails, especially in the counting phase, certain concentration which it is desirable to eliminate, so much more so since the number of characters of the terminal segment the composition of which the typist has just settled, does not present in itself any interest, and only the resulting setting of the justifier is of any importance.

The invention has as its object a process and setting devices by means of which the typist is freed from calculating, and even knowing, the number of surplus or deficit characters in the terminal segments, the setting of the justifier being effected through the agency of colors, to the exclusion of the use of numerical graduations or their differences.

To this effect, a system for reading the spaces from the margin by means of colors is fitted to the typewriter, a system to be adjusted at the beginning of the work and comprising two elements: a space scale and a reading indicator, of which only one is adjustable on its support. It being possible to make the support of either element a part either of the carriage or the frame, four combinations can be designed:

(a) The space scale is adjustable on the carriage and the reading indicator fixed on the frame;

(b) The space scale is fixed on the carriage and the reading indicator adjustable on the frame;

(c) The space scale is adjustable on the frame and the reading indicator fixed on the carriage;

(d) The space scale is fixed on the frame and the reading indicator adjustable on the carriage.

The space scale is constituted by a series of marks of different colors forming a parallel to the longitudinal axis of the typewriter, and, whichever of the above combinations (a) to (d) is adopted, the notches or holes of the setting scale of the justifier (setting scales if the typewriter comprises several normal terminal segments) are identified by marks of corresponding colors. At the beginning of the work, the adjustable element of the reading system is placed on its support in such a way that the central mark of the space scale, in other words the zero, coincides with the reading indicator when the last character of a normal terminal segment has just been printed. At the end of the blank typing of any terminal segment, the indicator points to a determined color of the space scale, and it is enough for the typist to set the justifier to the notch of the same color, without numerical preoccupation of any kind.

The invention will be well understood by the following description of its application to an end-of-line justifying typewriter with its carriage sliding in relation to the rack and the justifying lever pivoting on the rack, for the combination (a) above, i. e. adjustable space scale on the carriage and reading indicator fixed on the frame, the space scale being carried by the rule which holds the paper against the platen, the description being made with reference to the attached drawings in which:

Fig. 1 is a diagrammatic and partial plan view of such

a typewriter where the carriage is in the position for the beginning of justifications;

Fig. 2 represents an elevational view of a space scale on a removable clip;

Fig. 3 is a section along line III—III of Fig. 2;

Fig. 4 represents in plan view a modification of the removable clip shown in Fig. 2;

Fig. 5 represents in elevation another form of the removable clip;

Fig. 6 is a side view of Fig. 5;

Fig. 7 represents in elevation a space scale on a non-removable slider;

Fig. 8 is a side view of the above slider;

Figs. 9 to 12 show various forms which it is possible to give the different colored marks, on a space scale on a clip;

Fig. 13 shows a setting scale for a justifier, provided with circular colored marks, as in Figs. 2, 5 and 7;

Fig. 14 is a view of the same typewriter as in Fig. 1, where the carriage is in the position reached at the end of justifications.

In Fig. 1, B represents the frame of the typewriter, upon which the carriage Ch moves; the frame B is indicated by only a part of its outline. J is the terminal justifier mounted on the right of the carriage Ch, with its setting scale E and its justifying lever L which the stop k of the frame contacts from the beginning of justifications; k is carried by a slider m, adjustable on the rail m' of the frame. G is the guide of the typewriter, with the type guide f. The sheet of paper F is held against the platen H by the graduated paper bail or rule R, which can be turned up or down in the known manner, e. g., by rotation around shafts a, a', carried by the end plates t, t' of the carriage. The small rubber rollers r and r' holding the paper can slide on the paper bail R.

It is assumed that the typewriter is fitted, as are many of the recent models, with transparent plates such as p, articulated on the frame on each side of the guide G. Only one of these plates is represented, and the reading indicator i takes the form of a small arrow engraved on it. To give the typist more freedom in the disposition of the rollers r, r', contingent upon the size of paper used and the place that the justified column will occupy in the page, it is practical to provide a supplementary indicator 20' to 40 characters away from the first, e. g. at i', on the same plate p, as i, or on the symmetrical plate. It is evident that the indicators can be carried by any other part of the frame than a transparent plate. The continuation of the description supposes that the typist employs the indicator i.

In plan views such as those of Figs. 1 and 14, the graduations of the paper bail R, as well as the indicator i, would be hardly visible. For the clearness of the diagrams, the paper bail and the indicator are therefore represented such as they appear to the typist, i. e. approximately in elevation.

In accordance with the invention, the paper bail R is fitted with a movable scale e (space scale) of a length at least equal to the total justification range, for instance, a length of 9 characters if the range stretches from -4 to +4 characters. In the case of Fig. 1, the scale is held on a clip C, a member made removable in order to permit the sliding of the rollers r, r' up to the most convenient positions, in function eventually of the position which C will have, itself, to occupy. On the other hand, if the paper bail or rule R is free from obstacles from one end to the other, the scale can be established on a slider, a non-removable member of which the typewriter's technique offers numerous examples of construction.

Following the invention likewise, the space scale e consists of a series of different colored marks such as m (Figs. 1 and 2), in a number equal to the total justification play and with a distance of one character from each other; this series, which is parallel to the paper

bail or rule R, will move past the reading indicator *i* towards the end of the blank typing of the terminal segments, when the series of different colored marks will have been initially set on the rule for this purpose.

In the case of a removable clip (Figs. 2 to 6), the scale *e* can appear behind or in front of the rule, according to the structure of the typewriters to which the invention is applied, e. g. the space between the platen H and the rule R in working position, the degree by which the indicator *i* may be brought nearer the scale and the manner in which the reading is effected, etc.

Figs. 2 to 4 show one design of such a removable clip in which the space scale *e* appears behind the paper bail or rule. The clip C comprises a projection *o* for grasping and two hooks *c*, *c'*, by means of which it is clipped on the rule R. The hooks have a certain resiliency, in order to grasp the rule firmly, or else, it is the body of the clip which is designed spring-like, as shown in plan view in Fig. 4, in such a way as to flatten against the rule when it is forced on it. Figs. 5 and 6 illustrate a second design of removable clip, where the scale *e* appears in front of the rule R. The clip then clasps the rule with a spring effect between its back and front faces. In addition to general arrangements of this kind, given simply as examples, the base of the clip can be inclined towards the front or back, with a view to giving the scale *e* a better lighting, as indicated in dotted lines on the end views (Figs. 3 and 6).

In the case of a slider C' (Figs. 7 and 8), still for a carriage rule sliding in relation to a frame indicator, a window or opening *f* permits the graduations of the rule R to be seen. The upper part of the slider is roughened to facilitate its manipulation.

In the different examples mentioned above, the scale *e* appears beneath the graduations of the rule R: indeed, the carriage sliding on the frame, the indicator *i* is normally situated lower than the rule. When the rule is integral with the frame and the indicator *i* mounted on the carriage, it is on the contrary the reverse arrangement, i. e. the scale *e* above the graduations of the rule R, which is the most natural.

Still following the invention, each notch or hole of the setting scale E (Figs. 1 and 13) of the justifier (setting scales if the typewriter comprises several normal terminal segments), is identified by a mark such as N, preferably of the same form, and obligatorily of the same color as the mark *n* of the clip (or of the slider) to which it corresponds.

As to the form, the marks can take, for example, that of circular figures as in Figs. 2, 5 and 7, squares (Fig. 9), triangles with the apex turned towards the indicator (Fig. 10), vertical rectangles (Fig. 11), lozenges, ovals with a vertical axis, that is, in general terms, any regular forms likely to facilitate their visual separation at the normal observation distance. In all the cases, the zero marks of the space scale *e* and the setting scale E of the justifier can take a form different from that of the other marks, e. g. a simple line of some thickness, a small arrow, a figure larger than the others, or, else, smaller, an asterisk, etc., in order to stand out plainly on these latter. According to a modification, the series of marks corresponding respectively to the deficient terminal segments and to the overlarge terminal segments are of different forms, e. g. circular figures for the first series and triangles for the second (Fig. 12), the corresponding arrangement being duplicated naturally on the setting scale E of the justifier.

No numerical graduation exists therefore on the space scale *e*, this not excluding the eventual use of + and - signs on each side of the central mark, as well as a zero for this mark, as well as zero for this mark, such a symbol then being considered not as a figure, but as the particular design given to the said mark to differentiate it from the others, as explained above. On the other hand, the setting scale E of the justifier (the scales if the type-

writer comprise several normal terminal segments) is not necessarily free from such graduations; it can be useful indeed, for justifications from a preparatory copy having an uneven margin, to show the numerical value of the setting notches by some indications. From this point of view, the most convenient notches for numbering are those of +2 and -2, for, in combination with the central notch (or zero notch) identified by a particular mark, they graduate the scale E in a well-balanced and sufficient manner (Fig. 13). It must be well understood however, first, that these numberings in no way take part in the justifications at the first attempt, and, secondly, as will be shown below, that even the justifications after a preparatory typing do not necessitate their use.

It does not matter what the colors of the different marks are, on condition that they are easily distinguished one from another and they stand out from the backgrounds of the clip C (or slider C') and the scale E. The central marks being characterized by a special form, their color is of no great concern; for preference, however, they should be made black if the backgrounds of the clip C and the scale E are of light color, or white if these latter are dark. For a justification play of ± 4 characters, the colors of the marks can, for example, be the following, from left to right for the space scale *e* and from bottom to top for the setting scale E of the justifier, when the member shifting the carriage in relation to the rack (the justifying lever L in the typewriters of the kind shown in Fig. 1) turns clockwise during the justifications: yellow, red, blue, maroon, white or black (or no color at all) for the zero marks, orange, violets, green and beige.

It is not as easy as one would expect to compose a combination of eight or nine colors easily distinguishable one from another without tiring the eyes when these colors cover only very small and close surfaces. Practically, the number of necessary colors can be reduced to six.

In the great majority of cases, indeed, a justification play of ± 4 characters is more than necessary, and one at least of the notches +4 or -4 could be omitted. If they are both retained, it is, first, to meet certain solicitude for the symmetry in the presentation of the end-of-line justifying typewriters, secondly, for the occasional obtaining of special effects such as the execution of titles and sub-titles greatly dilated or contracted, corrections on stencils and duplimate, etc. In any case, these notches not serving in the justification routine where they could be accidentally confused with the others, and being, when special work is in progress, instinctively discernible from the others owing to their place at the ends of the scales, it is unnecessary to make them colored. In these circumstances, a group of six colors is sufficient. The choice of these colors as regards their mutual contrasts and their setting off from the backgrounds of the clip C and scale E is then easy. These colors can be, for example, in the same order as above: red, yellow, blue, for the three negative settings nearest the zero, and orange, green, violet for the next three positive settings; or else, in the same order: red, white and blue, then yellow, black and green, the zero marks not being colored or being black or white, but standing out plainly from the other marks due to their particular form, as already explained. Thus the contrasts necessary to an immediate perception of the colors on the space scale *e*, as well as to the reflex setting of the justifier by correspondence of colors—to the exclusion of any numerical reading or computation—are more easy to effect.

These various arrangements having been set forth, the initial settings for the justifications at the first attempt will now be described:

1. The leaf of paper F being rolled round the platen H, the right hand margin M (Fig. 1) which the typist wants to manage corresponds to a certain graduation of the rule R; let this graduation be 84, for example. If the normal terminal segment utilized comprises 30 characters, the justifications will have to begin at the graduation

85—30=55 of the rule (if it comprised 28 characters, they would begin at the graduation 85—28=57). The position which the clip C occupies on the rule R does not matter for the moment.

2. The typist brings the graduation 55 of the rule in the vertical plane of the type guide f (Fig. 1), sets the element of the frame (here the stop k) intended to contact a certain member of the justifier (here the justifying lever L) at the contact with this member, and then locks the said element in position. In this manner, at each passage of the graduation 55 past the type guide f, the justifier will go into action. Further, when the blank typings must be effected on the space bar, the typist sets the right hand margin stop (line lock) so that it stops the carriage at these passages; but, if the blank typings are effected on the keyboard, she contents herself with pushing the said line lock back to the end of the carriage—or of the frame, according to the structure of the typewriters—in other words, she puts the line lock out of the way. It is then the sounding of a bell which announces the arrival of the graduation 55 in the plane of the type guide f, as described in the application for patent Serial No. 300,072 filed July 21, 1952, under the title "Blank Typing of Terminal Segments."

3. In shifting the carriage 30 characters towards the left (Fig. 14), the typist brings the graduation 85 in line with the type guide f, then places the space scale e, i. e. the clip C (or the slider C') on the rule R so that its central mark coincides with one of the reading indicators, the indicator i, for example (she could just as well use the indicator i' by shifting the roller r' a few characters to the right). Thus, when the justifications start, the zero mark of the space scale e will be 30 characters to the right of the chosen indicator i and, after the impression of the last character of a normal terminal segment, the indicator i will point to this zero mark.

Of the above three operations, only the last, relative to the initial setting of the space scale, adds anything to the initial settings described in the aforementioned applications for patents. The properly termed justification operations being known, it is not necessary to review them, but that which concerns the actual setting of the justifier using colors, during justifications, must be explained.

The figures of the scale presenting, for example, the following colors, indicated above (still from left to right on the space scale e and from bottom to top on the setting scale E of the justifier): yellow, red, blue, maroon, black for the central mark, orange, violet, green and beige, if, at the end of the blank typing of a terminal segment, the indicator i points to the maroon figure which is one character to the left of the central mark, the segment comprises 29 characters; if it points to the violet figure, which is two characters to the right of the central mark, the segment comprises 32 characters. However, the typist has no need to know these numbers, no more than to know and to remember the numbers of the characters respectively lacking or in excess which are deduced from them. All she has to do is to set the justifier to the maroon or to the violet notch, without troubling herself in any way with numerals, the notches of these colors corresponding by construction to the settings —1 and +2 on the scale E of the justifier. Experience confirms that the setting of the terminal justifiers by correspondence of colors is surer, speedier and less tiring, in other words more automatic, than the setting by numerical graduations.

Although the above example concerns a normal terminal segment of 30 characters, it is clear that the invention applies whatever the number of characters of the normal terminal segment used, in particular for greater numbers, the justifications at the first attempt on typewriters with several normal terminal segments not necessarily implying obligation to use the shortest of these segments.

When typing the preparatory copy for justifications made after such a copy, it is useful to note the future setting of the justifier for each line. This is done conveniently by initially placing the space scale e on the rule R as indicated above in 3 for justifications at a first attempt, i. e. so that the central mark of the space scale coincides with the reading indicator i when the last character of a line the length of which is equal to the width of the desired column has just been typed. When the last character of any line of the preparatory copy has just been typed, the indicator i points to a mark of a determined position of the space scale, either left or right of the central mark. The position in question, with its sign (signs — or + engraved on the scale), indicates the setting which will suit this line. If the indicator shows, for example, the 2nd mark after the central mark, in the region covered by the + sign, the setting to be noted will be +2; if it shows the 3rd mark before the central mark, in the region covered by the — sign, the setting will be —3; finally, if it shows the actual central mark, the setting will be obviously zero.

The use of a special scale, numerically graduated from —4 to +4 could well be envisaged for the execution of preparatory copies, the colored scale being then relegated to a point of the rule R where its view would cause no inconvenience; still, the reading of figures necessarily small and close together not being very sure, whereas the estimation of the position of a mark from an easily distinguishable central mark is most easy (and all the less subject to errors as this position practically never exceeds 3 in justifications), such a scale would bring no notable advantage to the user.

Instead of noting the marks' position on the preparatory copy, the typist may note their color by means of abbreviations, and subsequently set the justifier to these colors, as for justifications at a first attempt. This explains what has been said above of the fact that the justifications after a preliminary typing do not call in any way for numbering the notches of the setting scale E of the justifier, even in a reduced manner, as in —2 and +2, for example, in Fig. 13. The setting of terminal justifiers on colors suits the two modes of justification.

The invention has been described for a typewriter in which the space scale is adjustable on the carriage, and the reading indicator secured to the frame. It must be well understood, however, as specified above, that its application to end-of-line justifying typewriters is not limited to such an arrangement, but that:

(Combination b above) the space scale can be secured to the carriage and the reading indicator adjustable on the frame; in this case, the space scale is engraved directly on the graduated rule of the carriage, its marks of different colors superposing themselves on the graduations of the said rule;

(Combination c above) the space scale can be adjustable on the frame and the reading indicator secured to the carriage; or else (Combination d above), the space scale can be fixed on the frame—it is then engraved directly on the graduated rule of this latter—and the reading indicator adjustable on the carriage. In these latter two cases, as the indicator moves past the scale from right to left during typing, the colors corresponding to the negative settings are to the right of the central mark, whereas the colors corresponding to the positive settings are to the left.

Finally, the invention does not concern simply the typewriters with a justifying lever pivoting on the rack taken, as example in the present description; on the contrary, it applies to all the types of end-of-line justifying typewriters described in the aforequoted applications for patents.

I claim:

1. In a justifying typewriter having a frame, a carriage shiftable thereon and justifying mechanism including a justifying member and setting means for said member; a color setting apparatus comprising a space scale, a series

of differently colored markings on said scale and spaced one character from each other, a reading indicator for said scale, said scale and indicator being mounted on said typewriter, one of said scale and indicator being adjustable, the relative positions of said scale and indicator being such that said indicator points to a zero mark on said space scale when the last character of a line equal in length to the width of the desired column has been printed or blank typed, a justifier setting scale associated with said member and a series of colored markings thereon corresponding to those on said scale.

2. In a justifying typewriter having a frame, a carriage shifttable thereon and justifying mechanism including a justifying lever, a color setting apparatus comprising a space scale, a series of differently colored markings on said scale and spaced one character from each other, a reading indicator for said scale, said scale and indicator being mounted on said typewriter, one of said scale and indicator being adjustable, the relative positions of said scale and indicator being such that when said indicator points to a zero mark on said space scale it indicates that the last character of a line equal in length to the width of the desired column has been printed or blank typed, the markings being of substantially the same geometrical form and taken from the class consisting of circles, rectangles, ovals and triangles, and a setting scale for the justifying lever provided with notches designated by

10 15 20

markings of the same character as those borne by the space scale.

3. In a justifying typewriter having a frame, a carriage shifttable thereon and justifying mechanism including a justifying lever and setting means for said lever including a scale having color designations, a color setting apparatus comprising a space scale, a reading indicator for said space scale, one of said space scale and indicator being adjustable, the relative positions of said space scale and indicator being such that said indicator points to a zero mark on said space scale when the last character of a line equal in length to the width of the desired column has been printed or blank typed, said space scale bearing color designations corresponding to those on the scale of the setting means whereby a color indicated on the space scale by the indicator will guide the operator in arranging the justifying lever according to a color on the setting scale corresponding to that designated on the space scale by said indicator.
